DESIGN FOR A SOAP HOLDER

Luigi Taddeo, Cleveland, Ohio, assignor to Arthur
A. Taddeo, Cleveland, Ohio

Application April 7, 1939, Serial No. 84,129

Term of patent 14 years

To all whom it may concern:

Be it known that I, Luigi Taddeo, a citizen of the United States, residing in Cleveland, in the county of Cuyahoga and State of Ohio, have invented a new, original, and ornamental Design for a Soap Holder, of which the following is a specification, reference being had to the accompanying drawing, forming part thereof.

I claim:

The ornamental design for a soap holder, substantially as shown.

LUIGI TADDEO.
